Primary Examiner — Nicole C Shiflet*Assistant Examiner* — Yen Le Southwood(57) **CLAIM**

The ornamental design for a food processor as shown and described.

DESCRIPTION

1. Food processor

1.1 : Front

1.2 : Back

1.3 : Top

1.4 : Bottom

1.5 : Right

1.6 : Left

The broken lines depict portions of the food processor that form no part of the claimed design.

The design represents an electric food processor for mixing, cooking or heating meals, particularly for children; It is characterized as follows, namely, by a base, a bowl, a working container with handle but also an integrated spatula; the working container is cylindrical; a control device is featured on the front part of the bowl but also a pouring spout at the level of the working container; the handle of the working container is arc-shaped; a removable spatula is fixed on the left side of the working container; several rows of ventilation holes are featured on the rear part of the bowl.
